UNITED STATES PATENT OFFICE.

PHILIP J. HARRAH, OF BLOOMFIELD, INDIANA.

FENCE-POST.

No. 846,202.

Specification of Letters Patent.

Patented March 5, 1907.

Application filed September 21, 1906. Serial No. 335,613.

To all whom it may concern:

Be it known that I, PHILIP J. HARRAH, of Bloomfield, in the county of Greene and State of Indiana, have invented certain new and useful Improvements in Fence-Posts; and I do hereby declare the following to be a full, clear, and exact description of the invention, such as will enable others skilled in the art to which it appertains to make and use the same.

The object of this invention is to provide in a fence-post composed of light sheet metal means for fastening wires thereto in such manner as to prevent their being accidentally disengaged and at the same time permit the wires to be readily released when it is desired to disengage them from the post.

The invention will be hereinafter fully set forth, and particularly pointed out in the claim.

In the accompanying drawings, Figure 1 shows a portion of a fence the posts of which are constructed in accordance with my invention. Fig. 2 is an enlarged view of a portion of a post. Fig. 3 is a longitudinal sectional view on line 3 3, Fig. 2.

In carrying out my invention the post 1 is made of light sheet metal and in respect to its general contour is of approximately scroll formation, with its longitudinal edges bent or curved inwardly toward each other. It is necessary, however, that it be provided with a flat front face 2. From this face I strike up a series of wire-retainers in the form of tongues 3. Each of these tongues at its base remains integral with the body of the post. It is bent or crimped outward at 4, thence inward at 5, and then again outward at 6. The outward bend 4 in conjunction with the inward bend 5 forms a pocket for the fence-wire 7. The inward bend 5 serves to retain the wire in the pocket, and the latter being at the base of the tongue, where such tongue forms part of the body of the post, pressure 45 against the fence-wire in the direction away from the post cannot effect the outward bending of the tongue. As shown in Fig. 1, when one post is set on a plane lower than an adjacent post the wire is prevented from 50 pulling upwardly and out of the pocket by reason of the inward bend 5. The extreme

end of the tongue being bent outward, as at 6, so as to normally occupy a plane outside that of the face of the post, permits of the ready insertion of a tool between the tongue 55 and the face of the post to force the former outward to allow of the release of the wire.

I am aware that it is not new to form tongues from the body of a fence-post, such tongues being projected through the slots or 60 openings of the resulting apertures; but in all such instances the posts are made of heavy sheet-steel, and the bend of the tongues has been such as to make the retention of the wires exceedingly insecure, such 65 wires being liable to pull out when the posts are on different planes and also liable to force the tongues outward by unusual pressure on the wires in the direction away from the posts. I am also aware that it is not new 70 to form lips at the edges of angular posts by means of grooves terminating in perforations for accommodating the fence-wires; but according to my invention the tongues are struck up from the flat face of the post, 75 and special perforations are not necessary, since wires are retained in the pockets formed at the base of the tongues where the latter are strongest and, furthermore, by the inward bend of the tongues the wires 80 are retained in their pockets, while by the outward bending of the free ends a tool may be readily inserted between the tongues and the posts to allow the wires to be released.

85 I claim as my invention—

A fence-post composed of light sheet metal bent to provide a flat face, tongues struck up from said flat face and bent outward and thence inward at points intermediate their 50 ends, said tongues forming, at their points of connection to the face of the post, wire-retaining pockets, the free ends of said tongues normally lying outside the plane of the face of the post.

95 In testimony whereof I have signed this specification in the presence of two subscribing witnesses.

PHILIP J. HARRAH.
